Primary Examiner — John Windmuller*Assistant Examiner* — John R Yeh(74) *Attorney, Agent, or Firm* — Cooper & Dunham LLP(57) **CLAIM**

The ornamental design for a spray mop, as shown and described.

DESCRIPTION

FIG. 1 is a front perspective view of a spray mop in accordance with the present design;

FIG. 2 is a front perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The broken lines in the figures represent portions of the spray mop that form no part of the claimed design.

The jagged lines shown on the handle of the spray mop illustrate the handle broken away for ease of disclosure and form no part of the claimed design.

1 Claim, 4 Drawing Sheets
